UNITED STATES PATENT OFFICE.

ARTHUR F. BLASIAS, OF GUILFORD, NEW YORK, ASSIGNOR, BY MESNE ASSIGNMENTS, OF FORTY-NINE PER CENT. TO WILLIAM BOHLEBER, OF NEW YORK, N. Y.

CONTROL FOR AERIAL MACHINES.

1,385,858.

Specification of Letters Patent. Patented July 26, 1921.

Application filed April 20, 1917, Serial No. 163,361. Renewed June 14, 1921. Serial No. 477,602.

To all whom it may concern:

Be it known that I, ARTHUR F. BLASIAS, a citizen of the United States, residing at Guilford, State of New York, have invented 5 certain new and useful Improvements in Controls for Aerial Machines, of which the following is a full, clear, and exact description.

The invention which constitutes the subject matter of this application relates to a control for aerial machines and is an improvement upon my co-pending application Ser. No. 89,517, filed April 7th, 1916. In my previous application the valve mechanism is mounted upon the control post. In 10 my present application I have mounted the valve mechanism directly on the cylinder of the servo-motor, and thereby have eliminated several connections between the valve mechanism and the cylinder, and have otherwise 15 simplified the construction illustrated and described in said application.

In the drawings,

Figure 1 illustrates diagrammatically a 20 plan view of a portion of a tractor biplane with parts broken away to show detail connections and constructions.

Fig. 2 illustrates a side view of the preferred form of elevator control showing, 25 among other things, the servo-motor, the control post and the walking beam to which the control post is connected.

Fig. 3 is an enlarged view of a portion 30 of the control post and the valve connections of the servo-motor for the horizontal rudder control or elevator control illustrated in Fig. 2, the valve arrangements being shown in section to illustrate the interior construction thereof.

40 Fig. 4 is a section taken on line 4—4 of Fig. 3.

Fig. 5 is a section taken on line 5—5 of Fig. 3.

Fig. 6 is a section taken on line 6—6 of Fig. 3.

Fig. 7 is a section taken on line 7—7 of Fig. 3.

Fig. 8 illustrates a modified form of servo-motor designed particularly to control the 50 ailerons or the vertical rudder.

Fig. 9 illustrates an enlarged view of the control mechanism for manipulating the aileron servo-motor.

Referring to the drawings in detail, the reference numeral 10 designates the body of the tractor provided with wings 11 (only one being illustrated), ailerons 12, propeller 13, rudder 14, elevators 15, rudder bar 16, and a seat 17 for the pilot.

The ailerons 12 are controlled by means of a servo-motor 18, the rudder 14 by the servo-motor 19, and the elevators 15 by means of a servo-motor 20. The servo-motor 18 and the servo-motor 20 are actuated by mechanism located immediately in advance of the seat 17. The specific means for actuating the servo-motor 18 comprises a hand wheel 21 pivotally mounted at 22 upon the arm of the control post 23, and the connections between the servo-motor and this hand wheel 21 comprises a cord 24 extending around pulleys 25, 26, 27, 28, 29, 30, 31 and the wheel 32 rigidly mounted upon the steering wheel 21. Cords 38^a and 39^a serve to connect the ailerons with the servo-motor 18. The turning of the wheel 21 in one direction serves to veer the ailerons in one direction and the movement of said wheel in the other direction serves to veer the ailerons in a reverse direction.

The connection between the servo-motor 20 and the elevator 15 comprises the control post 23, walking beam 33, arms 34 and 35 and cords 36 and 37, which are connected to each of the arms 34 and 35.

The connection between the servo-motor 19 and the rudder 14 consists of cords 38 and 39 connected at each end of the king post 40, which is rigidly mounted on the rudder 14. This servo-motor is controlled from the rudder bar 16, which is adapted to be actuated by the feet of the pilot, and operative connection between the servo-motor and rudder bar is established by means of the cords 41 and 42.

I have illustrated in the drawings and described above the various connections of the servo-motors employed with the ailerons, rudder and elevators. It may be stated at this point that the specific form of servo-motor for controlling the elevators preferably differs from the form of servo-motor which is employed to control the rudder and the ailerons. I will first proceed to describe in detail the mechanism for controlling the elevators by means of the servo-motor 20.

and will thereafter describe in detail the mechanism for controlling the ailerons and the rudder.

Located in proximity to the seat 17 is the pivoted walking beam 33 provided with the levers 34 and 35 previously described. To the control post 23, which is rigidly mounted upon the walking beam 33, is pivotally connected a control arm 43 (see Figs. 2, 3 and 4). This control arm is, in fact, a part of the control post but as each is adapted to serve purposes not served by the other I refer to them as separate elements for the sake of clearness of description. The control arm 43 is pivoted at 44 (see Figs. 3 and 4) to the control post 23 and the movement of the control arm about this pivot is determined by the adjustment of the set screws 45 and 46 (see Fig. 3) which come into contact with the upwardly projecting arm 47 of the control post 23. This movement of the arm 43 relatively to the control post is limited but sufficient for the purpose intended, as will be clear from the statement of operation below. It may be stated, however, at this point that the movement to the right (backward) as viewed from Fig. 3 results in a similar movement being imparted to the control post by means of the servo-motor. A movement of the control arm to the left (forward) results in a similar movement being imparted to the control post by said servo-motor. These movements are of course in turn transmitted, by the intermediate connections previously described, to the elevators.

The control arm 43 is provided with a rigid arm 48 projecting downwardly from the pivot 44. This arm 48 is connected through the link 49 to the lever 50 which actuates the various pilot valves of the servo-motor. The servo-motor proper (see Figs. 2 and 5) comprises among other things the cylinder 51, one end of which is pivotally connected at 87 to the control post, piston 53 and piston rod 54, the latter being pivotally connected to some fixed part 55 of the tractor. At 56 I illustrate a valve housing mounted upon the cylinder 51. Within this housing are contained the various valves and inlet and exhaust ports for controlling the admission of compressed fluid to and discharge of fluid from said cylinder whereby the cylinder may be moved either to the right or left (backward or forward) to actuate the control post, walking beam and elevators, it being understood that the movement of the control post in one direction raises the pivoted elevators and the movement of said control post in the opposite direction lowers said elevators. The specific construction of the various instrumentalities for controlling the admission of fluid to and discharge of fluid from said cylinder I will now describe in detail.

Referring particularly to Figs. 2, 3 and 5 it will be noted that the housing 56 is suitably mounted upon one end of the cylinder 51 and access may be had thereto by removing the cover plate 57. The lever 50 is pivoted at 58 on the interior of the housing and one end of this lever projects outwardly through the opening 59 and connects with link 49 as previously described. The housing is provided with a chamber 60 in constant communication, through the inlet 61, with a fluid pressure supply not shown. This chamber 60 is tapped by two ports 62 and 63 through one of which the fluid under pressure is adapted to flow to one side of the piston 53 and through the other of which the fluid is adapted to flow to the other side of said piston. Within the housing 56 are two inlet valves 64 and 65 and two exhaust valves 66 and 67, all of which are positively operated, normally closed by suitable springs, and respectively provided with stems 68, 69, 70 and 71. In the front and rear of valve 64 there are small chambers 72 and 73; in the front and rear of valve 65 there are chambers 74 and 75; in the front and rear of valve 66 there are chambers 76 and 77; and in the front and rear of valve 67 there are chambers 78 and 79. Connected to the chamber 72 is one end of a pipe 80, the other end of which is connected to one end of the cylinder to admit and discharge fluid from one side of the piston 53, and connected to the chamber 74 is one end of a pipe or conduit 81, the other end of which is connected to the other end of the cylinder to admit and discharge fluid from the other side of the piston 53. Communication is established between the chambers 72 and 77 by means of the passage 82 and a similar passage 83 establishes communication between the chambers 74 and 79. Connecting the chambers 76 and 78 are exhaust ports 84 and 85, leading to the atmosphere.

I have previously stated that the piston and piston rod of the servo-motor 18 is secured to some fixed part 55 of the machine. The other end of the servo-motor is provided with an arm 86 which is pivotally connected at 87 to the control post 23. Rigidly connected to link 49 is a horizontal rod 88 adapted to reciprocate back and forth in the housing 56.

The operation of the construction illustrated in Figs. 2 to 7 is as follows. In flying either one or both of the pilot's hands are on the steering wheel 21. A forward push on this wheel (as distinguished from a rotation of it) results in a corresponding movement of the control arm 43 upon which said wheel is mounted. It requires, at most, only a slight movement of the control arm around its pivot 44 to bring the adjustable set screw 46 into contact with the upper

end of the arm 47, but the adjustments of the valves and the length of the arm 48 are such that before this set screw contacts with the arm 47 the inlet valve 64 and exhaust valve 67 are opened by the movement of the lever 50 around its pivot in a counter-clock-wise direction. These valves will remain open until a quantity of air from the pressure chamber 60 has been discharged to the left of the piston 53 to force the cylinder 51, valve casing 56 and control post 23 sufficiently to the left so as to enable the pivoted lever 50 again to assume the position illustrated in Fig. 3 to permit the inlet valve 64 and exhaust valve 67 to close. This movement of the control arm therefore enables the servo-motor to lower the elevators, and the only force required, eliminating friction, in accomplishing this object is that required to open the inlet and exhaust valves. The compressed fluid in passing from the chamber 60 to the cylinder 51 traverses in succession the passages 62, chamber 73, chamber 72, and pipe 80. The exhaust from the other side of the piston takes place through the pipe 81, chamber 74, passage 83, chamber 79, chamber 78, and exhaust port 85. A movement of the control arm to the right (backward) opens the inlet valve 65 and exhaust valve 66 resulting in a movement of the servo-motor and control post to the right (backward). The opening of the inlet valve 65 establishes communication between the chamber 60 and that end of the cylinder to the right of the piston 53 through the intermediate passage 63, chamber 75, chamber 74 and pipe 81. The exhaust from the other side of the piston takes place through pipe 80, chamber 72, passage 82, chamber 77, chamber 76 and exhaust port 84.

From the foregoing it will be noted that the various valves contained in the servo-motor are always normally closed against both the inlet of pressure to and the exhaust of pressure from the cylinder 51. It will be obvious that should the servo-motor, for any reason, become inoperative the elevators may be directly controlled from the control arm. The upwardly directed arm 47 on the control post in that event will come in contact with the set screws 45 or 46 as the case may be and said control arm and control post can then be actuated as a unit. It will be noted, even in this event, that the various valves will be actuated as before in order to maintain atmospheric pressure on both sides of the piston 53. It may be mentioned that the control arm will be just as easy to manipulate or to maintain in a given position regardless of the atmospheric disturbances. A gust of wind, for example, impinging against the elevators will of course have a tendency to move the control post in a certain direction, but the movement of the control post automatically opens one of the inlet valves to admit pressure into the cylinder to resist this movement. The force, therefore, upon the control post, in any event, will only be, as previously stated, what is required to open one of the inlet valves and the corresponding exhaust valve.

In Fig. 8 I have illustrated a slightly modified form of arrangement of the servo-motor more particularly adapted to control the ailerons and the rudder. The valve mechanism is exactly the same as that illustrated in Fig. 3, but is more or less centrally located with respect to the cylinder 51^a, the latter being adapted to move longitudinally with respect to the shaft or piston rod 54^a, which shaft is fixed to posts or brackets 89 and 90 located upon the base 91. The movable cylinder 53^a is provided with a projection 88 to which the cords 38 and 39, or 38^a and 39^a are attached, depending upon whether the servo-motor is connected to the rudder or the ailerons. It will be noted, in connection with the modified form, that the principle of its operation is identical to the principles described in connection with the construction illustrated in Figs. 1 to 7 inclusive. Should the intermediary control fail to operate automatically, for instance due to the exhaustion of fluid pressure, the various parts will be actuated as before to maintain the pressure on both sides of the piston at one atmosphere, so that the part to be controlled can be actuated manually, as well as automatically. In the manual actuation of said part it will be understood with respect to the various modifications illustrated and described that the levers 50 and 50^a, when the parts are to be actuated manually, contact upon slight movements thereof about their pivots with some rigid portion of the valve housing. In the construction of housing illustrated these levers preferably contact with those portions which provide bearings for the valve stems 68, 69, 70 and 71.

The constructions illustrated and described herein are merely the preferred embodiments of my invention. It is to be understood that I do not limit myself to these exact constructions, as many changes may be made in points of detail and modifications resorted to without deviating from the true spirit and scope of my invention. It is also to be understood that I do not confine my invention to any particular type of flying machine. In the drawings I have illustrated in a diagrammatic way the application of my invention to a tractor bi-plane, and it is obvious that the adaptation of my invention to any other type of machine is clearly within the purview and range of the ordinary mechanic. Furthermore, I have purposely omitted to illustrate or describe the detailed mechanism of the tractor in order not to render the description unnecessary.

sarily prolix, and in this connection it may be stated that where a certain element is not illustrated and described any conventional form thereof may be employed.

5. What I claim is:

1. An intermediary control for flying machines comprising a control post, an arm manually operated and pivotally mounted upon the control post, a fluid pressure mechanism connected to and adapted to actuate said control post, and means carried by said mechanism and actuated by the control arm for admitting fluid to said pressure mechanism.
- 15 2. An intermediary control for flying machines comprising a fluid pressure actuating means, in combination with means connected to a part of the machine to be controlled and actuated by said actuating means, mechanism carried by said actuating means for admitting fluid thereto and discharging fluid therefrom, and common means to manually actuate said actuated means and to control said mechanism to permit the 25 flow of fluid to and the exhaust of fluid from said pressure actuating means, said pressure actuating means adapted to move substantially in synchronism with the movement of the manual means.
- 30 3. An intermediary control for flying machines comprising a fluid pressure actuating means, valve mechanism carried thereby for controlling the flow of fluid to and the exhaust of fluid from said actuating means, in 35 combination with means connected to a part of the machine to be controlled and actuated by said actuating means, and a manually movable means pivoted to said actuated means and adapted to actuate said valve 40 mechanism, said actuating means adapted to move substantially in synchronism with the movement of the manual means.
- 45 4. An intermediary control for flying machines, comprising a fluid pressure actuating means in combination with a control post operatively connected to a part of the machine to be controlled and actuated by said actuating means, valve mechanism carried by said actuating means, and a man- 50 ually operated arm pivoted to said control post and adapted to actuate said valve mechanism to control the flow of fluid to and the exhaust of fluid from said actuating means.
- 55 5. An intermediary control for flying machines, comprising a fluid pressure actuating means in combination with a control post operatively connected to a part of the machine to be controlled and actuated by 60 said actuating means, valve mechanism carried by said actuating means, and a manually operated arm pivoted to said control post and adapted to actuate said valve mechanism to control the flow of fluid to and the 65 exhaust of fluid from said actuating means,

said fluid pressure actuating means adapted to move substantially in synchronism with the movement of said manually operated control arm.

6. An intermediary control for aerial machines comprising a fluid pressure actuating means, in combination with a control post operatively connected to said actuating means and to an element of the machine to be controlled, valve mechanism carried by 75 said actuating means, a control arm pivotally connected to the control post and adapted to actuate said valve mechanism upon the movement of said control post to admit a quantity of fluid to and from said fluid 80 actuating means to resist the movement of the element to be controlled.

7. An intermediary control for aerial machine, comprising a fluid pressure actuating means, in combination with a control post 85 actuated by said pressure actuating means, said control post being operatively connected to an element of the machine to be controlled, valve mechanism carried by said pressure actuating means to permit a flow 90 of fluid thereto and exhaust of fluid therefrom, a manually operated control arm, and means on said control arm to actuate said valve mechanism upon the movement of the control post to resist the movement of the 95 element to be controlled.

8. A control for flying machines comprising an actuating means provided with valve mechanism thereon, in combination with means connected to a part of the machine to 100 be controlled and adapted to be actuated by the actuating means, manually movable means for actuating said valve mechanism, and means on said manual means for operating said actuating means upon the failure 105 of the operation of the automatic means.

9. A control for flying machines comprising means connected to a part of the machine to be controlled, a fluid pressure servo-motor including valve mechanism thereon, and 110 means common to the aforesaid means and to said valve mechanism for either actuating the aforesaid means manually or for controlling the flow of fluid to and from said servo-motor to actuate said means 115 thereby.

10. A control for flying machines comprising means connected to a part of the machine to be controlled, a servo-motor actuated by fluid pressure, valve mechanism carried by said servo-motor for admitting fluid pressure to and from said servo-motor, and means adapted to actuate the aforesaid means directly, or indirectly by actuating said valve mechanism and said servo-motor. 120 125

11. A control for flying machines comprising means connected to a part of the machine to be controlled, including a servo-motor provided with valve mechanism thereon, and means carried by the aforesaid means 130

- adapted to actuate the latter directly or adapted to actuate the same indirectly through the instrumentality of the servo-motor.
- 5 12. A control for flying machines, comprising means connected to a part of the machine to be controlled, including a servo-motor having valve mechanism thereon, in combination with actuating mechanism carried by and having pivotal movement with respect to said means, and means actuated by the movement of said mechanism about its pivot and connected to said valve mechanism for controlling the servo-motor.
- 10 13. A control for flying machines, comprising a pivotally mounted control post connected to a part of a machine to be controlled, a servo-motor for actuating the control post and provided with valve mechanism thereon, and actuating arm connected
- to the control post and movable as a unit therewith to operate said valve mechanism for controlling the servo-motor.
14. A control for flying machines, a movable cylinder connected to a part of the machine to be controlled, a piston and a piston rod for said cylinder fixed relatively to the machine, and means for admitting fluid under pressure to and for exhausting fluid from the opposite sides of said piston comprising valve mechanism carried by said cylinder and containing a plurality of inlet and outlet ports, valves for said ports, and means for actuating said valves to move said cylinder, the movement of said cylinder being proportional to the movement of said actuating means.
- 15 In testimony whereof I hereunto affix my signature.
- 20 ARTHUR F. BLASIAR.
